UNITED STATES PATENT OFFICE.

FERDINAND J. HAGEN, OF NEW YORK, N. Y., ASSIGNOR OF ONE-HALF TO
BENJAMIN H. HOMAN, OF SAME PLACE.

WAVE-MOTOR.

SPECIFICATION forming part of Letters Patent No. 616,615, dated December 27, 1898.

Application filed July 25, 1898. Serial No. 686,840. (No model.)

To all whom it may concern:

Be it known that I, FERDINAND J. HAGEN, a citizen of the United States, and a resident of the borough of Manhattan, city and State of New York, have invented certain new and useful Improvements in Wave-Motors, of which the following is a specification, reference being had therein to the accompanying drawings, in which—

10 Figure 1 is a side elevation. Fig. 2 is a plan view. Fig. 3 is a detail side elevation of the auxiliary pump. Fig. 4 is a detail horizontal section of said pump, and Fig. 5 is a detail sectional view of the means for varying the length of the pump-operating rod.

15 The invention relates to that class of wave-motors wherein a float which rises and falls on the waves is carried by suitable levers and through said levers operates a pumping mechanism which forces water into a pressure-reservoir or a suitable storage-tank, from which it is drawn to operate any suitable motor.

20 It has for its object to provide a motor wherein the force of the rising waves will be utilized for the main pumping operation, the force of the falling float performing a minor portion of the work.

25 The invention consists in the novel combination and arrangement of parts hereinafter described, and particularly pointed out in the claims appended.

30 Referring to the various parts by numerals, 1 designates the float, which is triangular in vertical section, is hollow, and its interior filled with cork. The upper side of the float is horizontal, while the front or rear sides, which contact with the water, incline inward and downward and meet at the vertical center of 35 the float. By reason of this formation the waves will act on the float with a great lifting force, and as the float is very light it will be readily lifted by the waves. Connected to this float near its lower edge (one on each of its 40 ends) are levers 2, whose other ends are pivoted on the sea-wall or other suitable place. To the top of the float, directly over the levers 2, are pivoted a pair of levers 3, which are parallel with levers 2 and have their inner ends secured to a horizontal shaft 4, mounted in bearings which are carried by a

suitable support. By means of the parallel levers the float will be maintained in substantially the same horizontal position throughout its movement. Mounted on the shaft 4 55 is an upright arm 5, which is connected at its upper end to a short link 6, which in turn is pivoted to the end of a horizontal reciprocating rod 7, mounted in bearings 8. The other end of this rod is connected to a link 9, 60 which in turn is pivoted to the downward-extending crank 10, secured to a rock-shaft 10^a, which is mounted in bearings 11. Secured to this shaft is a rearward-extending arm 11^b, in the rear end of which is mounted 65 a grooved roller 12, which works upon the under edge of a long rearward-extending lever 13, whose forward end is pivoted in a support 11^c above the rock-shaft 10^a. Connected to this lever 13 beyond roller 12 is a 70 depending link 14, whose lower end is connected to a piston-rod 15 of a single-acting pump 16. Mounted on the rear end of lever 13 is a weight 17, which may be adjusted thereon to secure the desired pressure on the 75 piston of pump 16.

75 The rod 7 is formed in two sections, and the adjoining ends of the sections are threaded in opposite directions and are connected by a correspondingly-threaded sleeve 18, which 80 is mounted to slide through bearings 19 and is formed with a longitudinal groove 20. Mounted on this sleeve is a worm-gear 21, formed with a rib which fits groove 20. Engaging this gear 21 is a worm 22, which is carried by a shaft 23 and rotated by means of a crank. By means of this mechanism the rod 85 7 may be varied in length, in order to secure the proper relative positions of the float and angle-lever 10. It will be obvious that any 90 other suitable mechanism may be employed for varying the length of this rod.

95 Extending forward from the rock-shaft 10^a is a lever 24, and to its forward end is connected a link 25, whose other end is pivoted to a piston-rod 26 of an auxiliary pump 27. The lower ends of pumps 16 and 27 are provided with suction-heads 28, which extend into a tank 29, which is adapted to contain a supply of water. To the outlet-valve of the 100 main pump 16 is connected a pipe 30, which is provided with a check-valve 31, and con-

nected to the outlet-valve of the auxiliary pump is a pipe 32, provided with a check-valve 33. Pipe 32 connects the auxiliary pump to a large elevated storage-tank 34. 5 Connecting the outlet-pipes of the two pumps to a pressure-tank 35 is a pipe 36, and in this pipe, adjacent the tank 35, is a check-valve 37 and a cut-off valve 38, and between pipes 30 and 32 this pipe 36 is provided with a cut-off valve 39. The pipe 32, between pump 27 and pipe 36, is provided with a cut-off valve 40, and adjacent the tank 34 it is provided with a cut-off valve 41.

From the pressure-tank 35 extends pipe 42, 15 which extends upward and is connected to the pipe 32 adjacent the elevated storage-tank 34. Near its connection with pipe 32 this pipe is provided with a stop-valve 43. Between this valve 43 and the main pressure-tank 35 the pipe 42 is connected to auxiliary pressure-tanks 44 by branch pipes. Adjacent these tanks these pipes are provided with check-valves 45 and cut-off valves 46. Each tank 44 is provided with a valved nozzle 47, 25 through which water is forced against a water-wheel 48 of suitable construction. The shafts of these wheels are provided with suitable belt-wheels, through which power is transmitted to any desired place. Under 30 these water-wheels and adapted to collect the water therefrom is a long trough 49, which carries the collected water forward to a large water-wheel 50 and delivers it thereon. After rotating this large wheel the water falls 35 into tank 29. A pipe 51 is arranged to deliver water from tank 34 to the top of water-wheel 50 to drive said wheel whenever the supply from wheels 48 is insufficient. In this pipe is a valve 52, which is connected by 40 suitable levers to a governor 53. By this means the governor automatically governs the amount of water flowing from tank 34.

In the pipe 42, between the main tank 35 and the auxiliary tank 44, is placed a reducing-valve 54, which limits the pressure in said auxiliary tanks, and connected to the main pressure-tank is a pipe 55, which contains a safety-valve 56 to regulate the pressure in said tank.

50 The tank 29 is preferably filled with fresh water; but where the apparatus is to be operated by the sea or other salt water and a supply of fresh water cannot be obtained for tank 29 salt water may be drawn up through 55 pipe 57, which is connected to the auxiliary pump and is provided with a check-valve 58 and a stop-valve 59.

The operation is as follows: The raising of 60 the float by the waves forces the bar 7 rearward and through rock-shaft 10^a raises weighted lever 13, thereby elevating the piston of the main pump and through lever 24, connected to rock-shaft 10^a, depresses the piston of the auxiliary pump. This fills the main 65 cylinder with water and empties the auxiliary cylinder. The falling of the float will now lower roller 12 from lever 13 and permit the

heavy weight 17 to force the water out of the main cylinder, and at the same time the descending float through arm 24 and rock-shaft 70 10^a will elevate the piston of the auxiliary pump. In this way the float in falling does no work except to fill the auxiliary-pump cylinder with water, while the force of the rising waves is utilized to expel the water from the 75 auxiliary pump and elevate the weighted lever, which latter when released expels the water from the main pump. In this way the greater force—namely, that derived from the rising of the float—is made to do the main 80 portion of the work, while the lesser force—that derived from the falling of the float—has a very small proportion of the work to perform.

By means of the apparatus shown the water 85 from the pumps may be utilized in various ways. By closing valves 41 and 43 the two pumps will force water into the pressure-tank 35 for use on the wheels 48. By closing valves 39 and 43 the main pump will force water into 90 tank 35, while the auxiliary pump will force water into tank 34. If when the wheels 48 are not in use or at any other time it is desired to permit water from pressure-tank 35 to pass into storage-tank 34, valve 43 is to be 95 opened. Whenever it is desired to utilize both pumps to force water into tank 34, valves 38 and 43 are to be closed.

To facilitate the adjusting of the weight 17 on lever 13, a rope and pulley-block 60 are 100 provided.

Having thus fully described my invention, what I claim, and desire to secure by Letters Patent, is—

1. In a motor the combination of a float 105 adapted to rise and fall with the water, a horizontal rod, means connecting said rod to the float so that said rod will be reciprocated by said float, a weighted lever adapted to be raised by said rod but to descend independently thereof, a pump adapted to be operated by the rising and falling of said weighted lever, substantially as described.

2. In a motor the combination of a float 115 adapted to be raised by waves, a horizontal rod adapted to be reciprocated by the rising and falling of the float, a rock-shaft connected to said reciprocating rod, a lever secured to the rock-shaft, a weighted lever adapted to be raised by the lever on the rock-shaft but 120 to descend independently thereof, a pump adapted to be operated by said weighted lever, whereby the raising of the float by the wave will raise the weighted lever and the falling of the float will permit the said lever 125 to complete the action of the pump.

3. In a motor the combination of a float, a weighted lever, a pump adapted to be operated by said lever, and means whereby the rise of the float will raise the weighted lever 130 and the fall of the float will release the lever and permit it to descend independently.

4. In a motor the combination of a float, a rock-shaft, means connecting the float to the

rock-shaft, oppositely-extending arms on said shaft, a pump adapted to be operated, by one of said arms, a weighted lever adapted to be operated by the other of said arms, a pump adapted to be operated by the falling of said lever, substantially as described.

5. In a motor the combination of a float, a reciprocating rod connected thereto, means for varying the length of said rod, two oppositely-extending arms on said rock-shaft, a pump adapted to be operated by one of said arms, a weighted lever adapted to be raised

by the other of said arms, these arms being so disposed that the weighted lever will be raised by the raising of the float, a pump 15 adapted to be operated by the weighted lever.

In testimony whereof I hereunto affix my signature, in the presence of two witnesses, this 22d day of July, 1898.

FERDINAND J. HAGEN.
